UNITED STATES PATENT OFFICE.

ARNOLD SCHÄRER, OF NEW YORK, N. Y.

HAIR-WAVER.

1,395,774.

Specification of Letters Patent.

Patented Nov. 1, 1921.

Application filed March 9, 1921. Serial No. 451,053.

To all whom it may concern:

Be it known that I, ARNOLD SCHÄRER, a citizen of the United States, and a resident of the city of New York, borough of Manhattan, in the county and State of New York, have invented a new and Improved Hair-Waver, of which the following is a full, clear, and exact description.

This invention relates to improvements in hair wavers, an object of the invention being to provide a novel form of hair waver, or rather a pair of coacting hair wavers which will impart that peculiar conformation, known as the Marcel wave to a strand of hair.

A further object is to provide a hair waving device, which will be simple and practical in construction and operation, so that a woman may use the waver at home to curl her own hair without the assistance of a professional hair dresser.

A still further object is to provide a device of the character stated, which may be manufactured and sold at a comparatively small cost.

With these and other objects in view, the invention consists in certain novel features of construction and combinations and arrangements of parts as will be more fully hereinafter described and claimed in the claims.

In the accompanying drawings:

Figure 1 is a view in side elevation of one of my improved hair wavers;

Fig. 2 is a similar view of the other hair waver, showing the tongue 8 in partially open position;

Fig. 3 is a view in section on the line 3—3 of Fig. 1;

Fig. 4 is a similar view on the line 4—4 of Fig. 1;

Fig. 5 is a similar view on the line 5—5 of Fig. 1;

Fig. 6 is a fragmentary perspective view illustrating the conformation of a strand of hair after my improved wavers have been applied, the dotted lines indicating the wavers in applied position; and

Fig. 7 is a view in side elevation illustrating a modification.

Referring in detail to Figs. 1, 3, 4, 5 and 6 of the drawings, my improved hair waver A, which is of celluloid or any other appropriate flexible material, comprises a pair of parallel arcuate comb members 5 connected at their ends by bridges such as 6 and

spaced apart throughout their length. Throughout the main portion of their length, the members 5 are provided with a series of teeth 7 disposed at an angle to the transverse axis of the comb members, the teeth of each member being parallel, and disposed at an opposite angle to the teeth of the other comb member.

An arcuate tongue 8 is pivoted at one end between the members 5 on a pin 9 and is removably locked between the other ends of the members. I have illustrated one form of locking means, which includes a pair of inwardly presented nipples on the members 70 5 engageable in a perforation 11 in the free end of the tongue 8. When the tongue is in locked position, its upper edge is flush with the upper uninterrupted edges of the members 5. 75

In Fig. 2 I have illustrated a waver B similar in all respects to the waver shown in Figs. 1, 3, 4, 5 and 6, with the exception that the teeth 12 are disposed at opposite angles to the teeth 7. Similar reference 80 characters have been applied to the parts of the waver B, which correspond to the parts of the waver A.

In applying either waver to a strand of hair, the tongue 8 is swung to open position 85 and the hair is introduced between the tongue and comb members 5. The tongue is then swung to closed and locked position forcing the hair into the relatively wide slots 13, which are provided between the teeth of the comb members. By virtue of the fact that the teeth on the comb members are disposed at opposite angles to the transverse axis of the members, the hair when forced to the inner ends of the slots will be not only 90 curled upwardly over the top of the tongue, but will be curled or twisted laterally because those slots which may have their outer ends in registration will have their inner ends at some distance apart. The waver B 100 serves to curl the strand of hair in an opposite lateral direction to the waver A and for this reason, it is convenient to use the two curlers together so that a uniform wave will be imparted to a strand of hair, as illustrated in Fig. 6.

It will of course be understood that the flexibility of the wavers permits the comb members to be bulged outwardly from the tongue when hair is introduced into the 110 wavers.

It will be evident that the wavers need

not be of the arcuate shape of the preferred form and I have illustrated a modified form of waver C in Fig. 7. This waver is similar in all respects to the wavers A and B with the exception that the comb members 14 and the tongue 15 are of straight instead of arcuate form.

Various slight changes and alterations might be made in the general form and arrangement of the parts described without departing from the invention and hence I do not wish to limit myself to the precise details set forth, but shall consider myself at liberty to make such slight changes and alterations as fairly fall within the spirit and scope of the appended claims.

I claim:

1. A hair waver including a pair of parallel comb members, means connecting the comb members at each end and spacing them apart, and a tongue pivoted at one end between the ends of the comb members and movable between the comb members.

2. A hair waver including a pair of parallel comb members, means connecting the comb members and spacing them apart, a tongue pivoted at one end between the ends of the comb members, and means for removably locking the free end of the tongue between the other ends of the comb members.

3. A hair waver including a pair of parallel comb members, means connecting the comb members and spacing them apart, a tongue pivoted at one end between the ends of the comb members, and means for removably locking the free end of the tongue between the other ends of the comb members, said means comprising inwardly presented nipples on the comb members, said tongue having a recess therein receiving said nipples.

4. A hair waver including a pair of comb members, means connecting the comb members and spacing them apart, said comb members including teeth disposed at an angle to the transverse axis of the comb members, a tongue pivoted at one end and movable between the said members.

5. A hair waver including a pair of comb

members, means connecting the comb members and spacing them apart, said comb members including teeth disposed at an angle to the transverse axis of the comb members, a tongue pivoted at one end between the ends of the comb members, and means for removably locking the free end of the tongue between the other ends of the comb members.

6. A hair waver including a pair of comb members, means connecting the comb members and spacing them apart, said comb members including teeth disposed at an angle to the transverse axis of the comb members, a tongue pivoted at one end between the ends of the comb members, and means for removably locking the free end of the tongue between the other ends of the comb members, said tongue having a recess therein receiving said nipples.

7. A hair waver comprising a pair of comb members, means connecting the ends of the comb members and spacing said members apart, each of said members including a series of teeth disposed at an angle to the transverse axis of the members, the teeth on the two members being disposed at opposite angles to each other.

8. In combination, a pair of hair wavers, means associated with one of said wavers for curling a strand of hair transversely and in one lateral direction, and means associated with the other waver for curling a strand of hair transversely and in the opposite lateral direction.

9. In a hair waver, a pair of arcuate parallel comb members, bridges connecting the ends of said members and spacing them apart, teeth on the members, the teeth of one member disposed at an opposite angle to the teeth of the other member, a tongue pivoted at one end between the ends of the comb members, and means for removably locking the free end of the tongue between the other ends of the members.

ARNOLD SCHÄRER.
